UNITED STATES PATENT OFFICE.

WILLARD GEORGE STEADMAN, JR., OF SOUTHBURG, CONNECTICUT.

TENT-PEG.

1,109,478.

Specification of Letters Patent.

Patented Sept. 1, 1914.

Application filed August 7, 1913. Serial No. 783,487.

To all whom it may concern:

Be it known that I, WILLARD G. STEADMAN, Jr., a citizen of the United States, and a resident of Southington, in the county of 5 Hartford and State of Connecticut, have made certain new and useful Improvements in Tent-Pegs, of which the following is a specification.

My invention relates to improvements in 10 tent pegs, and it consists in the combinations, constructions, and arrangements herein described and claimed.

An object of my invention is to provide a 15 peg having means for anchoring the same in the ground, thereby preventing the withdrawal of the peg until such time as it is desired to withdraw it.

A further object of my invention is to 20 provide a tent peg of the type described in which the anchoring means may be withdrawn into the peg, thereby permitting the peg to be readily pulled up.

A further object of my invention is to 25 provide a peg made of pipe having few working parts and being of relatively low cost of manufacture.

Other objects and advantages will appear in the following specification, and the novel features of the invention will be particularly pointed out in the appended claims.

My invention is illustrated in the accompanying drawing forming part of this application, in which—

Figure 1 is a side view of the device, certain parts being shown in section, Fig. 2 is a view similar to Fig. 1 showing the parts in another position, Fig. 3 is a section along the line 3—3 of Fig. 2, Fig. 4 is a detail section of a portion of the device, and Fig. 5 is a side view of a portion of the peg one of the anchors being shown in section.

In carrying out my invention I provide a pipe 1, preferably of metal, such as iron or steel, at the lower end of which is a cone 45 shaped cap 2 removable if so desired which constitutes the sharpened end of the peg. The pipe 1 is provided with a plurality of openings 3 near its bottom and is provided with a pair of aligned openings 4 near its 50 top, and with a groove 1^x at its upper edge to secure the chain to the anchors while driving the pipe.

Arranged to extend within the pipe 1 is a smaller pipe 5, having a closed end 5^x 55 provided with a central opening 5^y. The

pipe 5 has a pair of openings 6 arranged to register with the openings 4 in the pipe 1 when the peg is anchored, as will be explained later. At the upper edge of the pipe 5 is a groove 7.

The anchors are preferably three in number and consist of curved members 8 having rounded cam surfaces 8^x at one end and being provided with expanded heads 8^y at the other. As will be seen, the anchors 65 are thinner at the broadened edges in order to readily enter the ground. The anchors are attached at their inner ends by means of short pieces of chain to a common chain 9 which passes through the opening 5^y in 70 the bottom of the pipe 5, thence upwardly through the pipe and is secured by a hook 10 to a handle 11.

From the foregoing description of the 75 various parts of the device the operation thereof may be readily understood.

The anchors are drawn in by means of the handle 11 until their expanded edges 8^y engage the outer surface of the pipe 1, as shown in Fig. 4. This leaves only a 80 very small portion of the anchor projecting on the outside of the pipe. The pipe 1 is now driven into the ground in the usual manner, and when at the proper depth, the pipe 5 is driven downwardly. In order to 85 permit the latter pipe to be readily driven the chain 9 may be laid over in the groove 7. The driving of the pipe 5 downwardly forces the anchor 8 through the opening 3 laterally into the ground, and owing to 90 the curved form of the anchors the latter are inclined upwardly as shown in Fig. 2. The bar 11 may now be removed from the hook 10 and passed through the aligned openings 4 and 6 thus locking the parts 95 in position. The curved cam surfaces 8^x of the anchor 8 facilitates the driving of the pipe 5 and the outward movement of the anchor.

In order to remove the peg, the bar 11 100 is first withdrawn then the pipe 5 and the anchors may be pulled inwardly by means of the chain 9 and handle 11. The bar 11 may then be inserted in the aligned openings 4 and used as a handle for withdrawing the 105 pipe 1. It will be noted that the bar 11 may be used for a number of different purposes, thus doing away with additional handles or operating means. Besides being used for pulling the chain, for locking the 110

pipe 5 to the pipe 1, and for pulling the pipe 1, it may also be used as a cleat for the attachment of a rope or guy.

While the device described above is designed primarily for a tent peg, it will be understood that the device might be used in other ways as for tethering stock, for attachment of anchoring cables or guys for derricks, and for any other work where 10 a peg or post which may be firmly anchored to the ground is desired. Furthermore the peg may be made of any suitable material and any size without departing from the spirit and the scope of the invention.

15 I claim:

1. A tent peg comprising a pipe provided with a conical end and having openings in its side near its bottom, a plurality of curved anchors arranged to extend through 20 said openings, a flexible member secured to the inner ends of said anchors for withdrawing the major portions of said anchors into said pipe, and an inner pipe inclosing said flexible member and arranged to engage the 25 inner ends of said anchors for forcing them outwardly.

2. A tent peg comprising a pipe provided with a conical end and having openings in its side near its bottom, a plurality of

curved anchors arranged to extend through 30 said openings, a flexible member secured to the inner ends of said anchors for withdrawing the major portions of said anchors into said pipe, an inner pipe inclosing said 35 flexible member and arranged to engage the inner ends of said anchors for forcing them outwardly, and means for locking said inner pipe to said outer pipe.

3. A tent peg comprising an outer pipe provided with a conical end and having 40 openings in its side near its bottom and near its top, a plurality of anchors arranged to extend through said openings, said anchors being curved and being provided with expanded heads at one end and 45 with cam surfaces at the other, a common chain secured to the anchors at their cam surfaces, an inner pipe provided with a perforated bottom arranged to receive the 50 chain and adapted to bear on the cam surfaces of said anchors for forcing the anchors outwardly, a handle secured to one end of said chain, and means for locking said inner pipe to said outer pipe.
